UNITED STATES PATENT OFFICE.

HENRY E. A. RAABE, OF JERSEY CITY, NEW JERSEY.

DEVICE FOR CONTROLLING THE ADMISSION OF THE CHARGE TO THE CYLINDERS OF EXPLOSIVE-ENGINES.

1,264,436.

Specification of Letters Patent. Patented Apr. 30, 1918.

Application filed July 10, 1914. Serial No. 850,213.

To all whom it may concern:

Be it known that I, HENRY E. A. RAABE, a citizen of the United States, residing at Jersey City, in the county of Hudson and 5 State of New Jersey, have invented a new and useful Device for Controlling the Admission of the Charge to the Cylinders of Explosive-Engines, of which the following is a specification.

10 The object of my invention is to provide means for controlling the operation of the fuel atomizing valve described in my application for Letters Patent Serial Number 835,638, filed May 1st, 1914, in combination 15 with such valve gears as described in my application for Letters Patent Serial Number 841,802, filed May 29th, 1914, but it may also be used on engines provided with other valves, the design of which would permit 20 the use of such a device.

Another object of my invention is to provide means for stopping the engine in the shortest possible time and eliminating the danger of "running past."

25 Another object of my invention is to provide means by which the operator can adjust the time of opening of the inlet valves while the engine is in operation, without disturbing the adjustments of any other 30 parts of the engine, thus enabling him to obtain the best results under all conditions.

The invention will be fully described hereinafter, and the features of novelty pointed out in the claims.

35 Reference is to be had to the accompanying drawings, forming part of this specification, in which similar characters of reference indicate corresponding parts in the figures, in which Figure 1 is a vertical section through the controlling valve as applied to the charging valve in actual practice; Fig. 2 is a vertical section in a plane at right angles to Fig. 1 taken on the line 2--2 in Fig. 3; which latter is a sectional 45 plan view of the controlling valve taken on the line 3--3 in Fig. 2.

In Fig. 1, 10 is the upper part of the cylinder head provided with the cavity 13 containing the retort 14 which supports the 50 inlet valve body 16, both being held in place by studs and nuts 17.

The valve body 16 is provided with the valve 19, the dash pot 20, plunger 21, air channel 26, air tube 27 and air supply port 28, for the purpose described in a previous 55 application.

The cavity 52 in the cylinder head is the exhaust valve chamber. The rod 49 connects with, and receives its reciprocating motion from the exhaust valve, which is not 60 shown in the drawings. The upper end of the rod 49 is threaded and screwed into the circular nut 53 provided with the expanding set screw 54, which, when tightened expands the split end of the rod 49 so as to 65 lock the nut firmly in its position on the rod, thereby permitting adjustment of the position of the nut on the rod 49.

The bonnet 55 forms a cover for the exhaust valve chamber, and also is the main 70 body of the controlling valve, which latter consists of the divided sleeve 56, both sections of which are held against the circular walls of the valve body 55 by means of the expanding spring 57 fitted into a groove in 75 the internal flange 58.

The nut 53 is provided with the flanges 59 and 60 which engage with the flange 58 on the valve sleeve and thus impart the reciprocating motion of the rod 49 to the 80 valve sleeve 56 by impact.

In the wall of the valve body 55 is the aperture 61 which communicates by means of the tube 27 and the air channel 26 with the interior of the dash pot 20 of the charg- 85 ing valve.

The valve sleeve 56 is provided with an aperture 62 leading into the groove 63, which is cut at an angle with the center line of the valve, as shown in Fig. 2. The 90 groove 63 governs the opening of the aperture 61.

The guide plates 64 protruding through rectangular openings 65 in the walls of the valve body are securely clamped between 95 the two sections of the divided strap 66, fitted into a groove around the exterior of the valve body, and also engage with the slots 67 formed by the two sections of the valve sleeve 56, thus permitting the valve 100 sleeve to slide longitudinally, but any rotary motion can only be imparted to the

valve sleeve by rotating the strap 66 about its axis; for this purpose the strap is provided with the lever arm 68.

The lubricating oil is admitted through the hole 69, and after passing through the controlling valve it is finally used for lubricating the exhaust valve.

The hole 71 serves as an air vent, while the cap 70 excludes any dust and foreign matter.

The operation is as follows: Assuming the valves to be in the position shown in Fig. 1.

Compressed air is admitted to the cylinder 15 of the engine through the port 28 and the open charging valve 19, carrying with it a charge of oil vapor, and moving the piston of the engine due to the rise of pressure in the cylinder. When the pressure in the 20 cylinder has nearly reached that of the air receiver, the valve 19 closes due to the pressure upon its stem, thus bringing the top of the groove 25 above the edge of the valve stem guide and allowing a small quantity 25 of compressed air to flow into the dash pot chamber. But as long as the aperture 61 remains open to the groove 63, the air will escape from the dash pot chamber, through the channel 26, tube 27 and the aperture 30 62, finding a free outlet through the grooves between the sections of the sleeve 56, and therefore the dash pot 20 will not exert sufficient pressure upon the valve stem nuts to hold the valve 19 positively closed as long 35 as the pressure within the cylinder drops due to the advancing piston. However, if ignition takes place during the first stroke, further admission of air is automatically 40 prevented by the closing of the valve 19 due to the ignition pressure.

While the piston advances the exhaust valve will draw the valve sleeve 56 down until the edge of the groove 63 cuts off the escape of air from the aperture 61, causing 45 the pressure in the dash pot to rise, and therefore lock the valve 19 positively in its seat.

This cut off takes place during the early 50 part of the stroke and therefore the latter part of the stroke is completed by the expansion of the air within the cylinder or by the expansion of the product of combustion after ignition.

When the exhaust valve opens it moves in 55 the opposite direction, reversing the motion of the rod 49 and the valve sleeve 56. This reverse motion would naturally cause the groove 63 to uncover the aperture 61 during the exhaust stroke, causing the valve 19 to 60 open and the air to escape through the exhaust port, but as the valve sleeve 56 remains stationary due to the friction against the valve body wall, the flange 60 of the nut 53 must come in contact with the inter-

nal flange 58 in order to push the sleeve upward, and at the same time it covers up the aperture 62, thus preventing the escape of air from the dash pot and the opening of the charging valve.

During the next downstroke of the valve, 70 the sleeve 56 again remains stationary until it is drawn down by the flange 59, thus having the aperture 62 open for the air to escape at the proper time.

It is clear that the engine will run as a 75 compressed air engine as long as it receives its supply of air, and no ignition would take place but if the pipe leading to the port 28 is supplied with a valve, the air supply could be shut off, and the engine stopped. In such 80 a case, however, the engine would run for two or three revolutions on the amount of air trapped between the stop valve and the charging valve, and to prevent this, it may be stopped by rotating the valve sleeve 56 85 by means of the strap 66 and guide plates 65 until the end of the groove 63 is moved over to one side of the aperture 61, thus permitting no air to escape from the dash pot, causing the latter to keep the valve 19 locked 90 to its seat at all positions of the crank.

The groove 63 is placed at an angle with the center line of the valve sleeve, and therefore the communication between the groove 63 and the aperture 61 may be brought about 95 earlier or later during the stroke of the valve by rotating the valve sleeve respectively to the left or to the right by means of the strap 66 and guide plates 65. This rotary motion may be affected by moving the lever 68 directly by hand or by means of suitable connections.

The device hereinbefore described may be applied to compressed air engines as well as four stroke cycle internal combustion engines, but its preferred application is for 105 two stroke cycle engines of the type described in my pending applications: 557,548, April 26, 1910, 835,638, May 1st, 1914, and 841,802, May 29th, 1914.

The exhaust valve may be operated by any suitable means of either continuous or interrupted movement, but preferably by the continuous movement described in application Number 841,802.

The opening of the exhaust valve occurs, as in the usual manner, at or near the end 115 of the power stroke.

While I consider the construction shown in the accompanying drawings and described 120 in the specification, the most practical one, I do not consider it necessary to strictly adhere to it, as I could change the form by substituting a small puppet valve with a release mechanism in place of the sliding valve 125 sleeve 56, or I could substitute a flat slide valve or a semi rotary valve for the cylindrical slide valve, or have the controlling

valve incorporated integral with the exhaust valve, and I therefore set forth the object of my invention and what I claim as new, in the following claims:

5. 1. In an internal combustion motor having a pneumatically operated inlet valve, the combination of said inlet valve with a control valve for controlling the opening of said inlet valve by releasing the pressure 10 upon the closing piston of said inlet valve, said inlet valve having means controlling the flow of compressed air to hold said valve positively closed.

15. 2. In an internal combustion motor having a pneumatically operated inlet valve, the combination of said inlet valve with a ported control valve constructed to be operated by the exhaust valve, whereby the time of opening of the inlet valve is fixed by the action 20 of the exhaust valve upon the ports in the control valve, said ports being in communication with the pressure piston of the inlet valve and said inlet valve having means controlling the flow of compressed air to hold 25 said valve positively closed, for the purpose specified.

30. 3. In an internal combustion motor including a cylinder having a pneumatically operated inlet valve and exhaust valve mechanism, the combination with the said inlet valve of a control valve operated by the exhaust valve mechanism, whereby the time of opening of the inlet valve is fixed by the action 35 of the exhaust valve mechanism upon ports in the control valve, and a pressure piston coacting with the inlet valve and communicating with said ports.

40. 4. In an internal combustion motor including a cylinder having an inlet valve, a piston attached to the stem of said inlet valve, the cylinder arranged to permit said piston to be subjected to pressure for the purpose of operating said inlet valve by fluid pressure, an exhaust valve operated from the 45 motor, a controlling apparatus consisting of a valve body provided with a port which connects the interior of the valve body with the said cylinder, and a valve operatively connected with the exhaust valve for the 50 purpose specified.

55. 5. In an internal combustion motor having an inlet valve, a piston coöoperating with the stem of said inlet valve, a cylinder arranged to permit said piston to be subjected to pressure for the purpose of operating said inlet valve by fluid pressure, said motor adapted to operate an exhaust valve, a controlling apparatus consisting of a valve body provided with a port which connects the interior of the valve body with the piston of the inlet valve, and a valve operatively connected with the exhaust valve, said valve being constructed and arranged so as to open 60 the port in the valve body during the clos-

ing stroke of the exhaust valve and to close 65 said port during the opening stroke of the exhaust valve.

6. In an internal combustion motor having an inlet valve, a piston connected with the stem of said valve, a cylinder arranged 70 to permit the piston to be subjected to pressure for the purpose of operating the inlet valve, and valve mechanism whereby an exhaust valve operated from the motor, a controlling apparatus consisting of a valve 75 body provided with a port which connects the interior of the valve body with the piston of the inlet valve, and a valve for controlling the opening and closing of said port in the valve body, said valve being 80 provided with an auxiliary valve, and a port located so as to coincide with the port in the valve body during a part of a stroke of the exhaust valve, and to be closed by the auxiliary valve before and while it coincides with 85 the port in the valve body during the return stroke of the exhaust valve, and operative connections between the exhaust valve, the controlling valve and the auxiliary valve.

7. In an internal combustion motor having an inlet valve, a piston attached to the stem of the valve, a cylinder arranged to permit the piston to be subjected to pressure for the purpose of operating the inlet valve, a valve operating mechanism, driving 90 mechanism whereby said mechanism is driven from the motor, a controlling apparatus consisting of a valve body provided with a port which connects the interior of the valve body with the piston of the inlet 100 valve, and a valve for controlling the opening and closing of the port in the valve body, the latter valve being provided with an auxiliary valve, valve gearing, and a port located so as to coincide with the port in the valve body during a fraction of a stroke in 105 one direction imparted to the controlling valve by the valve gearing, and to be closed by the auxiliary valve before and while said port coincides with the port in the valve 110 body during the return stroke imparted to said controlling valve by the valve gearing, and suitable operative connection between the valve gearing, the controlling valve and the auxiliary valve.

8. In an apparatus for controlling the supply of gases to motor cylinders having an intake valve provided with a pressure chamber for operating said intake valve by fluid pressure, and a valve controlling mechanism 120 driven through suitable driving mechanism from the motor; said mechanism having a valve body provided with a port which connects the interior of the valve body with the pressure chamber of the intake valve, a 125 valve for controlling the opening and closing of said port in the valve body and suitable connection between said controlling valve

and the valve gearing; said controlling valve having a port, the form of which will permit it to coincide with the port in the valve body at different points of the stroke 5 imparted to the controlling valve by the valve gearing, and means whereby the point at which said ports are to coincide can be controlled relatively to the motion of the valve.

10 9. In an apparatus for controlling the supply of gases to motor cylinders having an intake valve provided with a pressure chamber for operating said intake valve by fluid pressure, and a valve operating mechanism, driving mechanism whereby it is driven from the motor; said controlling apparatus having a valve body provided with a port which connects the interior of the valve body with the pressure chamber of 15

the intake valve, a valve for controlling the 20 opening and closing of said port in the valve body and suitable connection between said controlling valve and the valve driving mechanism; said controlling valve having a port, the form of which will permit it to 25 coincide with the port in the valve body during the points of admission by the intake valve to the motor cylinder, through motion imparted to said controlling valve by the valve operating mechanism, and means 30 whereby said ports in the controlling valve can be prevented from communicating with the port in the valve body throughout its entire motion.

HENRY E. A. RAABE.
